THERMAL RESPONSIVE VENETIAN BLIND

John J. Grebe, Midland, Mich.

Application October 22, 1945, Serial No. 623,673

9 Claims. (Cl. 268—96)

1

This invention relates to Venetian blinds and particularly to a type thereof which will be self operating in response to either solar or ambient heat.

In providing sun shade means for windows and similar openings it has long been common to provide outside awnings of one type or another. These operate with a reasonable degree of satisfaction but yet have certain drawbacks and disadvantages. Among the more obvious of these drawbacks are their rather unsightly appearance, the frequent necessity of operating them from the outside of the building and, particularly, their lack of flexibility in that it is not usually possible for an awning to shade only the portion of a window which is receiving direct sunlight and leave other portions with an unimpaired view. Some of these disadvantages are avoided by using conventional inside Venetian blinds, but in doing so a great portion of the solar heat which an awning is able to keep out of a building is permitted to enter by inside Venetian blinds. Hence, even though inside Venetian blinds will provide shade and protect the interior of a room from the direct rays of the sun they will not keep the room nearly as cool as will an outside awning.

It is accordingly desirable to provide a means which will combine the neat appearance and flexibility of the Venetian blind with the more effective shading of an outside awning, and in addition provide independent and automatic operation of the various portions of the blind to keep the individual parts thereof properly adjusted in relation to the sunlight falling thereon at any given time. In this way the blinds will be open to admit sunlight in the morning and evening when the sun is low and its rays are not particularly hot, but will automatically close sufficiently to protect the interior of the building from excessive heat when the sun is high and/or hot. Further, in certain forms of the herein-after disclosed invention the elements of the blind operate individually so that where a part of the blind is in the shade it will remain open while the part of the blind which is in the sun will close.

It is further desirable that units which will meet the above outlined conditions shall be inexpensive to construct, easy to install, reliable in operation, and attractive in appearance.

Accordingly, the principal object of my invention is to provide an automatically operating Venetian blind applicable to the exterior of a window or similar opening in a building.

A further object of my invention is to provide an outside Venetian blind as aforesaid in which

the individual elements thereof operate independently of other elements.

A further object of my invention is to provide an outside Venetian blind having individually operating elements which will be inexpensive to construct, easy to install and reliable and accurate in operation.

A further object of my invention is to provide means for operating Venetian blinds automatically which will be applicable to a wide variety of specific installations including inside installations.

Other objects and purposes of my invention will be apparent to those acquainted with equipment of this type upon examining the accompanying drawing and reading the following disclosure.

In the drawings:

Figure 1 is a somewhat schematic view in central longitudinal section showing the manner of installing my outside Venetian blind onto a window.

Figure 2 is an enlarged detail view of two units of one form of my improved blind.

Figure 3 is a fragmentary front view of the form of my improved blind shown in Figure 2.

Figure 4 is a fragmentary front view of another form of my improved blind.

Figure 5 is an enlarged fragmentary end view of a further form of my improved blind.

Figure 6 is a form of my improved blind adapted for inside installation.

Figure 7 is an enlarged fragmentary end view of the form of my improved blind taken along the plane VII—VII of Figure 4 showing a typical installation of one of the shading elements in open position.

Figure 8 is a fragmentary view of the form of my improved blind shown in Figure 7 and taken along the plane VIII—VIII of Figure 7.

Figure 9 is a fragmentary end view of a further form of my improved blind showing a typical installation of one of the shading elements.

Figure 10 is a fragmentary view of the form of my improved blind shown in Figure 9 and taken along the plane X—X of Figure 9.

Referring first to Figure 1 there is shown a fragment of an ordinary window frame 1 having therein a conventional lower window 2 and an upper window 3. Outwardly of the conventional blind stop 4 there is mounted for pivoting in the plane of the broken line 6 in any of the several ways shown hereinafter the individual blind slats 5 which, as shown in Figure 1, may occupy a series of different and independent positions.

This particular series of positions as shown in Figure 1 would meet, for example, the condition where a low tree or shrub shaded the lower part of the window but the upper part was exposed to the full strength of the sun's rays. The elements thus assume such a position that the upper portion of the window is shaded from the sun's rays, indicated by the broken lines in Figure 1, but at the lower portion the elements are open to sufficiently admit the maximum amount of light.

Forms shown in Figures 2-4

Referring now to Figures 2 and 3 there is shown one form of specific construction. A blind element 7 holds at its one end a pivot rod 9 which is pivotally supported by a bracket 8 of any convenient type, said bracket being suitably fastened to the window frame 10. At the other end the blind element is supported by a connecting plate 11 onto a control wafer 12 which is mounted onto the window frame 13 by any suitable bracket means 14 and 15. It should be understood, however, that this particular embodiment shown is only an example of several others which will be selected in a given case according to the specific needs which have to be met. For example the control wafer 12 may be duplicated on each end of the blind element 7 in larger installations, or where a more exacting control is desired. Further, the control wafer 12 may be mounted directly onto the blind slat 7a (Figures 4, 7 and 8) and appear as a long relatively narrow element 12a for the more positive controlling of the blind slats. When such an arrangement is employed the blind slat 7a as well as the control wafer 12a is interposed between the ends of the lower pivot bracket 102 dividing said bracket into an upper portion 103 and a lower portion 104. The lower portion 104 is attached to the lower surface of the blind slat 7a and the upper portion 103 is attached to the control wafer 12a. A further variation (Figures 9 and 10) would replace the blind slat entirely by an elongated expandable control wafer 105 having a cross-section substantially similar to the diametric cross-section of the control wafer 12 and mounted in a similar manner whereby the slat and the control wafer are combined into a single element.

The control wafer 12 (Figure 2) has a mounting plate 16 on its one side and a mounting plate 19 on its other side. To these mounting plates are secured the pivot brackets 17 and 18, respectively. An upper bracket 18 is fastened to the window frame in a convenient manner, and the lower bracket 15 is likewise fastened to the window frame in any convenient manner. The upper bracket 19 extends a short distance from the surface of the window frame, the exact magnitude of which distance will be determined by the relevant design details in any given installation. A connecting link 21 is pivoted at 22 to the upper bracket 19 and at 23 to the upper pivot bracket 18 of the control wafer. The lower supporting bracket 15 is fastened pivotally at 24 to the lower pivot bracket 17 of the control wafer. The length of the connecting link 21 and the arrangement of all parts are such that a line 25 from the pivot point 22 through the pivot point 23 will fall outwardly with respect to the building of a line 26 drawn from the pivot point 22 through the pivot point 24 for reasons appearing hereinafter. Thus the link 21 and the wafer with its pivot brackets form an outwardly bent toggle based at point 24, wherein the lower, or shorter, leg of the toggle is extendible.

The wafer 12 is constructed of corrugated metal of sufficiently thin section to be flexible and is formed into a body having a gas tight hollow interior. This interior is filled with any one of a number of low boiling materials, such as chloroform, methyl or ethyl alcohol, or ethyl ether. However, it should be understood that any material can be used within the wafer which will boil at or a little below the temperature at which it is desired to have the blinds closed. Since the actual closing will be a function of the pressure developed within the wafer as well as a function of the boiling by itself, the exact turning point will be determined by both the choice of liquid and the amount thereof put within a given wafer. This, however, is conventional with respect to wafers of this type and hence need not be set forth at length here. A desirable temperature for the turning of the blind slats is approximately 95° F. so that the character and amount of the liquid used may advantageously be chosen to cause expansion of the wafer under substantial pressure at that temperature.

The expanding of the wafer may also be controlled by the manner in which it is colored or coated. By using a dark or heat absorbing color the wafer will be extremely sensitive to the sun's rays and cause the slats of the blind to respond thereto with relatively little regard for the actual air temperature surrounding. On the other hand by providing the wafer with a mirror-like, or other reflecting, surface the sun's rays will have little effect thereon and the response of the wafer will be primarily to the air temperature surrounding.

Referring again to Figure 2 it will be seen that when the wafer is caused to expand it will exert a pressure tending to open the angle between the broken lines 25 and 26. This then causes the pivot point 23 to move to the right to assume the position shown in the lower half of Figure 2 and thus cause the slat 7 to pivot around the pivot point 24 and assume the position indicated in the lower half of Figure 2.

It will be evident that by proper selection of link and bracket lengths and angles the degree of turning of the slats can be made practically anything that is desired, but normally the amount shown will be satisfactory. It will usually not be desirable to have the slats closed completely inasmuch as shade from the sun is all that is intended for this apparatus and the slats should hence remain sufficiently open to permit air circulation.

Form shown in Figure 5

In the form shown in this figure the wafer is placed in the upper member of the toggle, the member corresponding to the arm 21 of Figure 2 and the lower member of the toggle is merely a short rigid arm affixed to the blind slat. In this form a bracket 40 is provided identical with the bracket 15 of the form in Figure 2. The blind slat 7, however, is directly pivoted by any suitable means to said bracket at the pivot point 41. In the form shown an end plate 42 is provided having a substantial area and provided with openings 43 and 44 for adjusting, as by fastening screws, the blind slat 7 at a selected one of a plurality of possible angles with respect to the operating arm 45. The said operating arm is integral with the plate 42 and pivots in any conventional manner at the point 46 to the upper arm 47 of the toggle. The wafer 48, being here the same as the wafer 12 in the form shown in Figure 2 is inserted between the lower part 49 and the upper 50 of the said toggle member 47.

Its expansion or contraction according to solar heat or ambient temperature, as determined by its surface finishing, causes said arm to lengthen or contract and the blind slat 7 to rotate around the point 41 accordingly. The lower part of Figure 5 shows the wafer in an expanded condition, and the blind slat consequently in its sun shading position.

There is also illustrated in Figure 5 a variation in the shape of the slat which may be equally well applied to any of the other forms here shown. This variation is the making of the slat of somewhat corrugated or wavy cross-section in order to break up reflection of the sun's rays from the surface of the slat and thereby prevent objectionable reflection or glare.

Form shown in Figure 6

This form of blind is intended primarily for inside use and as shown in Figure 6 is mounted inside of the window by hanging from the top of the window casing immediately inside of the window sash.

A vertical support 60 is affixed in a suitable manner to a base 61 which is in turn fastened to the undersurface of the upper part 62 of the window casing. The blind slats 63 are pivoted in any conventional and convenient manner as points 64 to said supporting rod 60 and are movable pivotally with respect thereto.

The operating rod 65 is similarly pivoted at points 66 to the blind slats 63 and is affixed at its upper end to a wafer 67 of the same general type as above illustrated and described in detail with respect to the form shown in Figure 2. This wafer is then fastened to a supporting element 68 which is in turn affixed to a base 69, which may or may not be integral with the base 61, and said base is affixed to the window frame.

It will be evident upon inspection of the figure that as the wafer 67 expands or contracts in response either to the sun's rays entering the window, or in response to the room temperature, the operating rod 65 will be caused to move downwardly or upwardly and the blind slats accordingly closed or opened.

Although this form has been shown for inside installation, it will be evident that this construction, hanging as it does from a single overhead support, will be applicable to either inside or outside installation.

It will be evident that many variations may be made upon the broad principles herein disclosed to fit a wide variety of specific circumstances. For example, other temperature responsive elements, such as a bimetallic element, may be substituted for the expanding wafers shown, without altering the major principle of my invention. Accordingly, my development is believed to be of broad application, and such variations will all be included within the scope of my hereinafter appended claims excepting where said claims themselves expressly limit otherwise.

I claim:

1. In a heat responsive, automatically operating sun shading means, the combination: a substantially rectangular sun shading element; means for pivotally supporting said element on one of its ends; a bracket for pivotally mounting said element in fixed relation with an opening in the wall of a building; a heat responsive, expandable element affixed on one of its sides to said shade element for pivoting therewith and extending in a direction away from said bracket; a link pivoted to the other of said sides of said ex-

pansible means and extending therefrom substantially oppositely to the above mentioned bracket; a second bracket affixed rigidly with respect to the building wall and pivoted to the free end of said link.

2. In a heat responsive, automatically operating sun shading means, the combination comprising: a substantially rectangular sun shading element; a toggle unit including a pair of pivotally mounted links; means rigidly mounting said shading element to one link of said toggle unit; means providing a thermally responsive source of linear mechanical motion integral with and constituting a portion of one of said links whereby variations in the length of said link in response to changes in temperature controls the pivotal position of said shading element.

3. In a temperature responsive automatically sun shading means, the combination comprising: a plurality of individual shading elements; a plurality of brackets each pivotally supporting one end of each of said shading elements; a plurality of pairs of pivotally attached toggle members each pair mounted to one of said brackets, one toggle member of each pair being rigidly attached to one of said shading elements; a thermal responsive linearly fluctuating element integral with and mounted intermediate the ends of and constituting a portion of one of said toggle elements whereby thermal changes are translated into fluctuations in length of said toggle element for changing the pivotal position of said shading element.

4. In a temperature responsive automatically operating sun shading means, the combination comprising: a plurality of individual shading elements; means pivotally supporting one end of each of said shading elements; base means at the other of the ends of each of said shading elements; a plurality of pairs of pivotally jointed toggle members each pair pivotally mounted to said base means at the other of the ends of each of said shading elements, one toggle member of each pair being rigidly attached to one of said shading elements; a thermal responsive linearly fluctuating element mounted intermediate the ends of and constituting a portion of one of said toggle elements whereby thermal changes are translated into fluctuations in length of said one toggle member for changing the pivotal position of said shading element.

5. In a temperature responsive automatically operating sun shading means, the combination comprising: a plurality of individual shading elements; means pivotally supporting one end of each of said shading elements; base means at the other of the ends of each of said shading elements; a plurality of pairs of pivotally jointed toggle members each pair pivotally mounted to said base means at the other of the ends of each of said shading elements, one toggle member of each pair being rigidly attached to one of said shading elements; a thermal responsive linearly fluctuating element mounted intermediate the ends of and constituting a portion of the other member of each pair of said toggle elements whereby thermal changes are translated into fluctuations in length of said other toggle member for changing the pivotal position of said shading element.

6. In a temperature responsive automatically operating sun shading means as described in claim 5 wherein the central axis of said shading element is co-axial with the point of pivotal

mounting of said one toggle element to said supporting means.

7. In a temperature responsive automatically operating sun shading means, the combination comprising: a plurality of individual shading elements; a bracket at one end of each of said shading elements; means at the other of the ends of each of said shading elements for pivotally supporting said shading element; a plurality of pairs of pivotally jointed toggle members, the free ends of each pair pivotally mounted to said bracket in fixed spaced relationship; one toggle member of each pair rigidly attached to one of said shading elements; a thermal responsive lineally fluctuating element mounted intermediate the ends of and constituting a portion of one of said toggle elements whereby thermal changes are translated into fluctuations in length of said one toggle member for changing the pivotal position of said shading element.

8. In a temperature responsive automatically operating sun shading means, the combination comprising: a plurality of individual shading elements each constituting a thermal responsive unit for fluctuations in thickness; a bracket at one end of each of said shading elements; means at the other of the ends of each of said shading elements for pivotally supporting said shading elements; a plurality of pairs of pivotally jointed toggle members, the free ends of each pair pivotally mounted to said bracket in fixed spaced relationship; one of said shading elements rigidly attached to one toggle member between the ends of said toggle member and in the direction of thickness fluctuation constituting a portion of said toggle member, whereby thermal changes are translated into fluctuations in length of said

one toggle member for changing the pivotal position of said shading element.

9. In a temperature responsive automatically operating sun shading means, the combination comprising: a plurality of individual sun shading elements; base means at each of the ends of said shading elements; a plurality of pairs of pivotally jointed toggle members, one of said pairs of toggle members pivotally mounted to said base means at each of the ends of each of said shading elements; one toggle member of each pair being rigidly attached to one end of one of said shading elements; a thermal responsive lineally fluctuating element mounted intermediate the ends of and constituting a portion of one of said toggle elements whereby thermal changes are translated into fluctuations in length of said one toggle member for changing the pivotal position of said shading element.
